DESIGN FOR A CABINET FOR REMOTE CONTROL APPARATUS

David C. Rockola, Chicago, Ill.

Application August 8, 1940, Serial No. 94,311

Term of patent 3½ years

To all whom it may concern:

Be it known that I, David C. Rockola, a citizen of the United States, residing at Chicago, in the county of Cook and State of Illinois, have invented a new, original, and ornamental Design for a Cabinet for Remote Control Apparatus, of which the following is a specification, reference being had to the accompanying drawing, forming a part thereof.

Figure 1 is a perspective view of a cabinet for

remote control apparatus showing my new design;

Figure 2 is a side elevation of the cabinet showing one side wall, the opposite side wall being similar in design, while the rear wall is plain.

I claim:

The ornamental design for a cabinet for remote control apparatus, substantially as shown and described.

DAVID C. ROCKOLA.
